UNITED STATES PATENT OFFICE.

LUDWIG KERN, OF HAMBURG, GERMANY.

KILN OR OVEN.

1,206,547.

Specification of Letters Patent. Patented Nov. 28, 1916.

Original application filed June 22, 1914, Serial No. 846,490. Divided and this application filed January 4, 1916. Serial No. 70,217.

To all whom it may concern:

Be it known that I, LUDWIG KERN, a subject of the Emperor of Germany, and a resident of Hamburg, Germany, have invented 5 a new and Improved Kiln or Oven, of which the following is a full, clear, and exact description, this being a division of the application for Letters Patent for an artificial building material and method for producing 10 the same, Serial No. 846,490, filed by me on June 22, 1914.

The object of the invention is to provide a new and improved kiln or oven more especially designed for burning bricks formed 15 of a mixture of infusorial earth and clay, and arranged to permit of first passing a current of air over the green bricks to reduce the moisture thereof, to then subject the bricks to heat of 650° to 950° centigrade 20 to burn or harden the bricks, and to finally pass another current of air over the burned bricks to quickly cool the same.

In order to produce the desired result, use is made of a housing provided with 25 horizontal perforate partitions forming a plurality of chambers or compartments one above the other, and of which the lowermost one is a combustion chamber and the others are receiving chambers for the reception 30 of the bricks to be burned, furnaces arranged in the sides of the housing and opening into the combustion chamber, the furnaces having ash pits provided with doors at their outer ends and opening at their 35 inner ends into the said combustion chambers to permit the circulation of air through the chambers prior to and after the burning of the bricks in the said receiving chambers. Use is also made of draft holes in the sides 40 of the said chambers, and dampers arranged in the perforations of the said partitions at the middle thereof to divert the heat to the sides of the receiving chambers.

A practical embodiment of the invention 45 is represented in the accompanying drawings forming a part of this specification, in which similar characters of reference indicate corresponding parts in all the views.

Figure 1 is a cross section of the kiln; 50 Fig. 2 is a reduced side elevation of the same with the housing in section and some of the side doors of the furnace and air inlets omitted; and Fig. 3 is a front end elevation of the kiln.

The housing A of the kiln or oven is built 55

on a suitable foundation and is provided with an interior lining B of fire clay or other fireproof material. The front end of the housing A is provided with suitable doors D, D', in front of which are arranged 60 platforms E, E', for carrying the bricks to be burned into the interior of the housing A and removing the burned bricks therefrom. The housing A is provided with horizontally disposed perforate partitions F, F', 65 F², dividing the interior of the housing into two chambers or compartments G and G' for receiving the bricks and into a bottom combustion chamber G² and a top chamber G³, from which latter extends a chimney H, 70 the bottom H' of which is likewise perforate, as indicated in Fig. 1. The bricks to be burned are set in the usual manner on the partitions F' and F², as indicated in dotted lines in Fig. 1, and with the sides 75 spaced from the sides of the lining B to permit a proper circulation of air and heat, as hereinafter more fully explained.

The sides of the housing A are provided with furnaces I for burning coke or other 80 fuel and opening into the combustion chamber G², the furnaces I on two sides of the kiln being arranged in staggered relation to each other, and each furnace is provided with a suitable door I'. The ash pit J for 85 each furnace I opens at its inner end into the combustion chamber G² for admitting air into the said combustion chamber prior to starting up the furnaces I so as to subject the bricks in the compartments G and G' to 90 the action of a strong current of air. The outer ends of the ash pits J are provided with suitable doors J'.

In order to prevent the air and the heat emanating from the burning fuel in the furnace I from rising centrally through the chambers G, G' and G³ to the stack H, it is desirable to close the middle perforations F³ of the partitions F, F' and F² during 95 the beginning of the firing of the furnace I, 100 and for this purpose the said middle perforations F³ are preferably closed by suitable dampers K mounted on rods K' extending to the outside of the kiln and adapted to be turned by the operator to open and close the 105 said dampers and consequently the middle perforations F³. Thus when all the dampers are closed, the air and heat from the combustion chamber G² pass upwardly through the open side perforations F³ of the parti- 110

tion F^2 through the bricks resting on the said partition. The air and heat next pass through the side perforations F^3 in the partition F' and rise through the stack of bricks set on the partition F' , and the air and heat finally pass through the side perforations F^3 in the upper partition F to finally reach the top compartment G^3 from which the air and heat pass up, next, into the chimney H and out of the same. The sides of the housing A are further provided with draft holes L leading into the compartments $G-G'$, which holes not only permit observation of the burning of the bricks in the said compartments, but perform a more important function of admitting atmospheric air to the compartments when needed during the process of burning.

The operation is as follows: The bricks are set in staggered relation into the chambers or compartments G and G' , and then the doors D , D' are closed and the doors J' are opened so that air may have free admission to the compartments G^2 , G' , G and G^3 and through the bricks set in the compartments G and G' . This is due to the fact that the kiln acts like a huge chimney, creating an upward draft. The air removes some of the moisture contained in the bricks and then the furnaces I are started so as to cause the resultant products of combustion to circulate through the compartments G^2 , G' , G and G^3 and through the bricks to burn the same. Owing to the use of clay of a low melting point it requires but a comparatively short time (say from 3 to 6 hours) to complete the burning of the bricks, and then the fires in the furnaces are drawn and the doors J' are fully opened to allow air to circulate through the bricks to quickly cool the same. It is understood that at the beginning of the operation the dampers K are preferably closed to prevent the bricks on the centers of the stacks from being subjected to an injurious concentrated high heat, but after the bricks have been somewhat burned the dampers K are opened to insure uniform burning of all the bricks in the stack.

In order to enable the workmen to properly form the stacks of bricks in the chambers or compartments G and G' , the parti-

tions F' and F^2 are provided near the sides with raised ledges F^4 to form guides for forming the stacks, as will be readily understood by reference to Fig. 1. The inner faces of the lining B are provided with lugs B' to prevent obstruction of the passages between the sides of the stacks and the inner facing of the lining in case some of the bricks in the stacks should become displaced and fall against the said faces of the lining.

It is understood that a brick burned in this kiln or oven is formed of a mixture of infusorial earth and a low grade clay melting at a temperature of 650° to 950° Celsius is of a desired strength of compression, porous, fireproof and of low specific gravity.

It is understood that with the opening and closing of the doors J' the doors L' of draft holes L are opened and closed to assist in supplying the desired amount of fresh air to the compartments, as above explained.

Although the kiln is mainly intended for burning bricks of a mixture of infusorial earth and clay, it is evident that the kiln may be used for burning articles other than bricks and made of other materials than the one mentioned.

Having thus described my invention, I claim as new and desire to secure by Letters Patent:

A kiln comprising a housing having horizontal perforate partitions dividing it into a plurality of chambers, one above the other, the lowermost one being a combustion chamber and the one next above a brick-receiving chamber, a furnace arranged in the sides of the housing and opening into the combustion chamber and adapted to permit admission of air for circulation through the chambers prior to and after burning of the bricks in the receiving chambers, and slideable dampers arranged horizontally in the perforations of the said partitions at the middle thereof to divert the heat to the sides of the receiving chambers, as specified.

In testimony whereof I have signed my name to this specification in the presence of two subscribing witnesses.

LUDWIG KERN.
